DETACHABLE ANTI-SLIPPING ATTACHMENT
FOR SHOES

Tom R. Scott, Jefferson City, Mo.

Application February 20, 1952, Serial No. 272,556

8 Claims. (Cl. 36—7.7)

1

This invention relates to a detachable anti-slipping attachment for the soles of footwear such as shoes, boots or the like, and has for an object to provide an improved anti-slipping shoe attachment particularly intended for use on the footwear of persons who are climbing mountains or scaling heights, so that they may have a firm footing at all times, irrespective of the type of surface over which they are walking or climbing, and irrespective of the angle at which that surface may be.

A further object of this invention is to provide an improved detachable anti-slipping attachment for footwear which is readily adjustable to fit various sizes of footwear but once it has been adjusted to a particular size, it may be readily attached to or detached from the footwear without the use of any tools whatsoever, and when attached, will remain firmly attached, irrespective of any strain that may be placed thereon by the wearer.

A further object of this invention is to provide a detachable anti-slipping attachment to be attached to the soles of footwear which includes a toggle locking means so that when the shoe is attached, the toggle provided by the locking means prevents any possibility of accidental release of the locking means and detachment of the anti-slipping attachment.

Still a further object of this invention is to provide a detachable anti-slipping attachment for the soles of footwear wherein the anti-slipping means thereon extends from the toe end area of the sole to somewhat beyond the ball of the foot end area of the sole. Means are provided for clamping this attachment to the sole which means is located at the toe end area of the sole and at the ball of the foot area of the sole as a result of which the foot and the footwear may flex about the ball of the foot away from the instep area, as it would naturally do when scaling a steep incline, yet leave the entire anti-slip area of the attachment in firm contact with the surface of the ground, ice, or rock over which the wearer is climbing.

A further object of this invention is to provide a detachable anti-slipping attachment for footwear which provides a ground gripping area under substantially the entire half-sole area of the footwear yet permits normal flexing of the footwear and normal walking operation of the foot.

Still a further object of this invention is to provide a clamping means including clamping lugs adjustably secured to different parts of the attachment so that the attachment may be fitted to any size of footwear within a wide range.

Still a further object of this invention is to provide an anti-slipping attachment for footwear wherein two plates are pivoted together at one end with their pivoting movement con-

2

trolled by a toggle mechanism at the other end, one plate fitting smoothly against the sole of the footwear and the other plate having an anti-slipping means provided thereon, the pivotal movement of the plates toward the overlapping direction under the action of the toggle means serving to clamp the attachment to the footwear.

With the foregoing and other objects in view, this invention comprises the combination, construction and arrangement of parts hereinafter set forth, claimed and disclosed in the accompanying drawings, wherein:

Fig. 1 is a side edge view of the attachment of this invention in operative position on a shoe.

Fig. 2 is a bottom plan view of the attachment with the parts shown in sole attaching position.

Fig. 3 is a top plan view of the attachment in sole releasing position.

Fig. 4 is a perspective view of the linking lever.

Fig. 5 is a perspective view of the operating lever.

Fig. 6 is a perspective view of one of the front clamping lugs.

Fig. 7 is a perspective view of one of the rear clamping lugs.

There is shown at 10 the detachable anti-slipping attachment for shoes of this invention arranged to be detachably clamped to the sole 11 of a shoe 12. The attachment 10 consists of a top plate 14 which in shape and size is about the shape and size of a half-sole of a shoe, having a finger 15 extending toward the shank for cooperation with the operating means. As seen in Fig. 1, the attachment 10 including the top plate 14 is bent or curved upwardly at both ends corresponding to the normal longitudinal curvature of the sole 11. A bottom plate 16 is provided likewise shaped like the half-sole of a shoe, but somewhat longer at the shank area at 17 to provide a portion cooperating with the clamp operating means.

The bottom plate 16 is provided with a plurality of rows of studs 18 here being shown as tongues struck out of the metal of the plate 16 to extend in a downward direction therefrom. Obviously, any types of caulk or studs may be provided integrally or detachably on this anti-slipping bottom plate 16. It will be noted that the rows of studs 18 extend from under the toe end area at 20 to beyond the ball of the foot area at 21.

Two transverse channels 22 and 23 are provided in the bottom plate 16, being integrally formed therein and extending downwardly therefrom of just sufficient depth to receive therein the securing arms 24 of the front sole clamping lug 25 and the rear sole clamping lug 26. Each of the arms 24 is provided with a plurality of threaded apertures 27 therethrough so as to receive the threaded shanks of the flat headed

screws 28 therein, a pair of screws 28 being provided for each clamping lug 25 or 26. Two suitable apertures are located adjacent one end of each channel 22 and 23 for receiving the shanks of the screws 28 therethrough, and for convenience in manufacture, similar apertures may be placed at the opposite ends of the channels so that the blanks for forming the bottom plate may be stamped by the same die for the right as well as the left shoe before the plate has the channels or studs formed therein.

The top plate 14 has a pair of correspondingly located apertures therethrough, which when the plates 14 and 16 are in overlapped clamping position, will lie over the opposite ends of the channels 22 and 23 from which the lugs are secured adjacent the channel ends. At this opposite end, similar lugs 25 and 26 are secured by similar screws 28 through the suitably located apertures. The top plate 14 is provided with a depending or downwardly extending flange 30 integral therewith and located between the lugs 25 and 26 on that side, and the bottom plate 16 is provided with an upstanding flange 31 correspondingly located on its opposite edge likewise between its clamping lugs 25 and 26. At the toe end area of the plates 14 and 16, they are pivotally secured together as by a rivet 31. At the other end, an operating lever 32 having an operating handle 33 at one end thereof, is pivoted by means of a rivet 34 to the shank area 17 of the anti-slipping bottom plate 16 on its upper surface. Inasmuch as the top plate 14 is likewise pivoted at 31 to the bottom plate 16, it is apparent that the lever 32 will move substantially in the plane of the top plate 14. A linking lever 35 shaped substantially as shown is pivoted a tone end 36 to the projecting finger 15 of the top plate 14, it being noted that this finger 15 is curved slightly upwardly at 37 from the plane of the plate 14 to thereby provide space between the overlapped plates for the pivoting end of lever 35.

The other end of lever 35 is bent or shaped at 38 so as to raise its other end 40 above the plane of the operating lever 32 and permit it to be pivoted thereto by means of a rivet 41, and to lap thereover in operation.

It will be noted that this entire operating mechanism consisting of the operating lever 32 and link lever 35 extends over the shank area 17 of the bottom anti-slipping plate 16 and the upturned handle 33 may fit along the edge of the sole 11 when in closed position.

In operation, the screws 28 may be removed by a suitable screw driver to adjust the clamping lugs 25 and 26 to the proper size to fit the particular shoe 12 on which it is to be worn, a left foot attachment being shown in the drawing, and a right foot attachment would obviously be a mirror image of that herein shown. Then when the clamping lugs are fitted to the right size, to attach the attachment in operative position on the sole of the footwear, it is merely placed under the sole and the operating lever handle 33 is moved from the position shown in Fig. 3 in a clock-wise position as viewed in Fig. 3 to the position shown in Fig. 2. As the operating lever 32 is moved about its pivot 34, it pulls the link lever 35 causing the upper plate 14 and anti-slipping bottom plate 16 to pivot about their pivot 31 to the overlapped position with the flange at one edge of each plate brought into abutment with the adjacent edge of the other plate. At the same time, the line between the centers of the pivots 36 and 41 moves slightly beyond the

center of the pivot 34 just as the handle 33 approaches and abuts a flat edge 42 of the top plate 14 as shown in Fig. 2, thus providing a toggle effect, and thus locking the attachment in the clamped position, for obviously any tendency of the plates 14 and 16 to move away from each other about their pivot 31 would then cause the operating lever 32 to press more tightly against the flat edge 42 of the plate 14, thus making it impossible for accidental separation to take place, thus keeping the attachment firmly clamped to the shoe sole.

To release the attachment when it is no longer needed on the shoe sole, the wearer may grasp the upstanding handle end 33 of the operating lever 32 and move it in the opposite direction away from the flat edge 42 about its pivot 34, thus overcoming the toggle effect and then moving the plates 14 and 16 to partially separated position, thus releasing the clamping lugs 25 and 26 from engagement with the edges of the shoe sole 11.

The term "shoe" as used throughout this specification and claims is to be interpreted as meaning any type of footwear having a sole to which this attachment is capable of being clamped.

While the device has been shown and the structure described in detail, it is obvious that this invention is not to be considered as being limited to the exact form disclosed, and that changes in detail and construction may be made therein within the scope of what is claimed, without departing from the spirit of this invention.

Having thus set forth and disclosed the nature of this invention, what is claimed is:

1. A detachable anti-slipping attachment for shoes comprising a half-sole-shaped top plate, a similar but longer anti-slipping bottom plate, pivot means at the toe end area securing said plates together, a pair of front shoe clamping lugs and a pair of rear shoe clamping lugs, one lug of each pair being adjustably secured to said bottom plate, the other lug of each pair being adjustably secured to the bottom of said top plate and toggle link means for pivoting said plates to shoe clamping section.

2. A detachable anti-slipping attachment for shoes comprising a half-sole-shaped top plate, a similar but longer anti-slipping bottom plate, pivot means at the toe end area securing said plates together, an upstanding flange on one side

edge of said bottom plate and a similar depending flange on the opposite side edge of said top plate limiting the relative pivoting of said plates to overlapping position in one direction, a pair of front shoe clamping lugs and a pair of rear shoe clamping lugs, one lug of each pair being adjustably secured to said bottom plate, the other lug of each pair being adjustably secured to the bottom of said top plate and toggle link means for pivoting said plates to shoe clamping position.

3. A detachable anti-slipping attachment for shoes comprising a half-sole-shaped top plate, a similar but longer anti-slipping bottom plate, a pair of transverse channels depressed in said bottom plate, one channel extending under the toe area, the other channel extending under the ball-of-the-foot area, means at the toe end area securing said plates together for pivotal movement, a pair of front shoe clamping lugs and a pair of rear shoe clamping lugs, one lug of each pair being adjustably secured to said bottom plate and located one in each transverse channel adjacent the same ends thereof, the other lug of each pair being adjustably secured to the bottom of said top plate adjacent the opposite ends of

said transverse channels, and toggle link means for pivoting said plates to shoe clamping position.

4. A detachable anti-slipping attachment for shoes comprising a half-sole-shaped top plate, a similar but longer anti-slipping bottom plate, a pair of transverse channels depressed in said bottom plate, one channel extending under the toe area, the other channel extending under the ball-of-the-foot area, means at the toe end area securing said plates together for pivotal movement, an upstanding flange on one side edge of said bottom plate and a similar depending flange on the opposite side edge of said top plate limiting the relative pivoting of said plates, a pair of front shoe clamping lugs and a pair of rear shoe clamping lugs, one lug of each pair being adjustably secured to said bottom plate and located one in each transverse channel adjacent the same ends thereof, the other lug of each pair being adjustably secured to the bottom of said top plate adjacent the opposite ends of said transverse channels, and toggle link means for pivoting said plates to shoe clamping position.

5. A detachable anti-slipping attachment for shoes comprising a half-sole-shaped top plate, a similar but longer anti-slipping bottom plate, a pair of transverse channels depressed in said bottom plate, one channel extending under the toe area, the other channel extending under the ball-of-the-foot area, means at the toe end area securing said plates together for pivotal movement, an upstanding flange on one side edge of said bottom plate and a similar depending flange on the opposite side edge of said top plate limiting the relative pivoting of said plates, a pair of front shoe clamping lugs and a pair of rear shoe clamping lugs, one lug of each pair being adjustably secured to said bottom plate and located one in each transverse channel adjacent the same ends thereof, the other lug of each pair being adjustably secured to the bottom of said top plate adjacent the opposite ends of said transverse channels, and toggle link means for pivoting said plates to shoe clamping position.

6. A detachable anti-slipping attachment for shoes comprising a half-sole-shaped top plate, a similar but longer bottom plate, a plurality of anti-slipping studs providing an anti-slipping surface on the bottom of said bottom plate, a pair of transverse channels depressed in said bottom plate, one channel extending under the toe area, the other channel extending under the ball-of-the-foot area, means at the toe end area securing said plates together for pivotal movement, depending flange on the opposite side edge of said top plate limiting the relative pivoting of said plates to overlapping position in one direction, a pair of front shoe clamping lugs and a pair of rear shoe clamping lugs, one lug of each pair being adjustably secured to said bottom plate and located one in each transverse channel adjacent the same end thereof, the other lug of each pair being adjustably secured to the bottom of said top plate adjacent the same end thereof, the other lug of each pair being adjustably secured to the bottom of said top plate adjacent the opposite ends of said transverse channels, and toggle link means for pivoting said plates to shoe clamping position.

bottom of said top plate adjacent the opposite end of said transverse channels, and toggle link means for pivoting said plates to shoe clamping position.

7. A detachable anti-slipping attachment for shoes comprising a half-sole-shaped top plate, a similar but longer bottom plate, a plurality of anti-slipping studs providing an anti-slipping surface on the bottom of said bottom plate, said studs being tongues integrally struck out from said bottom plate and arranged in rows extending transversely of said bottom plate, said rows being located from the toe end area to beyond the ball-of-the-foot area, a pair of transverse channels depressed in said bottom plate, one channel extending under the toe area, the other channel extending under the ball-of-the-foot area, means at the toe end area securing said plates together for pivotal movement, an upstanding flange on one side edge of said bottom plate and a similar depending flange on the opposite side edge of said top plate limiting the relative pivoting of said plates to overlapping position in one direction, a pair of front shoe clamping lugs and a pair of rear shoe clamping lugs, one lug of each pair being adjustably secured to said bottom plate and located one in each transverse channel adjacent the same ends thereof, the other lug of each pair being adjustably secured to the bottom of said top plate adjacent the opposite ends of said transverse channels, and toggle link means for pivoting said plates to shoe clamping position.

8. A detachable anti-slipping attachment for shoes comprising a half-sole-shaped top plate, a similar but longer bottom plate, a plurality of anti-slipping studs providing an anti-slipping surface on the bottom of said bottom plate, said studs being tongues integrally struck out from said bottom plate and arranged in rows extending transversely of said bottom plate, said rows being located from the toe end area to beyond the ball-of-the-foot area, a pair of transverse channels depressed in said bottom plate, one channel extending under the toe area, the other channel extending under the ball-of-the-foot area, means at the toe end area securing said plates together for pivotal movement, an upstanding flange on one side edge of said bottom plate and a similar depending flange on the opposite side edge of said top plate limiting the relative pivoting of said plates to overlapping position in one direction, a pair of front shoe clamping lugs and a pair of rear shoe clamping lugs, one lug of each pair being adjustably secured to said bottom plate and located one in each transverse channel adjacent the same ends thereof, the other lug of each pair being adjustably secured to the bottom of said top plate adjacent the opposite ends of said transverse channels, and toggle link means for pivoting said plates to shoe clamping position.
